CLAIM

The ornamental design for a frozen confection product, as shown and described.

DESCRIPTION

FIG. 1 is a front, top, right side perspective view of a frozen confection product showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1–5 and 7 illustrate the environment of the claimed design and form no part thereof.
